UNITED STATES PATENT OFFICE.

DANIEL F. BEAMAN, OF HOUSTON, TEXAS, ASSIGNOR TO THE TEXAS COMPANY, OF NEW YORK, N. Y., A CORPORATION OF TEXAS.

DISPENSING DEVICE.

Application filed August 4, 1920. Serial No. 401,263.

To all whom it may concern:

Be it known that I, DANIEL F. BEAMAN, a citizen of the United States of America, and a resident of Houston, county of Harris, and State of Texas, have invented certain new and useful Improvements in Dispensing Devices, of which the following is a specification, reference being had to the accompanying drawings, forming a part thereof.

My invention relates to the dispensing of liquids and semi-solids, and particularly to means for measuring and dispensing oils and greases.

One object of my invention is to provide a simple and durable apparatus of the aforesaid character that shall be adapted to dispense relatively heavy oils and greases with facility.

Another object of my invention is to provide an effective and improved valve mechanism capable of adaptation to a large variety of uses. Other objects and advantages of my invention will be set forth hereinafter.

Referring to the drawings:

Figure 1 is a partially sectional elevation of a grease dispensing pump, arranged and constructed in accordance with my invention, and constituting one embodiment thereof.

Figure 2 is a plan view of the same mechanism.

Figure 3 is a sectional elevation showing the principal elements of the pump in detail, the valves being shown in the position occupied during the suction stroke of the pump.

Figure 4 is a view corresponding to Figure 3, but showing the valves adjusted to the position occupied during the discharge stroke of the pump.

Figure 5 is a sectional plan view taken on the line 5—5 of Figure 3. Corresponding parts are designated by the same reference characters in each of the figures.

The structure illustrated comprises a base 10, a supply tank or box 11, a top casting or plate 12, secured to the base by tie rods 13, a cylinder 14, a piston 15 operating therein, an outer cylindrical guide casing 16, which is formed integral with the bottom head 17 of the cylinder, and a pair of

interposed semi-cylindrical sleeve valves 18 and 19 between the cylindrical casing 16 and the cylinder 14.

The cylinder 14 has a relatively large inlet port 20, and a large outlet port 21, which is opposite the inlet port. The casing 16 has an opening 22 registering with port 20 and is connected to the tank or box 11 by means of a short section of pipe or conduit 23.

The casing 16 is provided with an outlet or discharge well 24, having an opening 25 in register with the outlet port 21, a discharge pipe 26 being screwed into the mouth of the well 24. A flexible pipe or tube 27 is secured to and forms a continuation of the pipe 26 and has at its outer end a discharge nozzle 28.

The piston or plunger 15 is connected to an actuating lever 29 by means of a piston rod 30 which is pivotally attached to the plunger at one end and to the lever at the opposite end.

The lever 29 terminates in a handle 33, is fulcrumed at 31 on a lug 32 with which the top casting 12 is provided, and is of a suitable length to enable the pump to be operated without undue effort on the part of the attendant. The movement of the lever in a downward direction is limited by an adjustable stop 34 which may comprise a set screw extending through a tapped hole in the lever and having a set nut 35 as shown in Figure 1.

The valves 18 and 19 may be operated in any suitable manner. In the arrangement illustrated in the drawings a valve operating lever 36 is provided and is connected on opposite sides of its fulcrum 37 to the respective valves by valve rods and links 38 and 39.

The lever 36 is extended to provide a convenient handle 40 and has a bell crank formation so that a limited oscillating motion is permitted. The arrangement of parts is such that the valves operate alternately in opposite directions, the outlet valve 18 being closed when the inlet valve 19 is open, 100 and vice versa.

The operation of the apparatus will be clearly understood from the foregoing description, but may be outlined as follows:

Assuming that the tank or box 11 which 105 may for example be a five gallon grease can,

is at least partially filled with a heavy liquid or semi-solid substance such as grease, and the handle 33 is pushed down and the handle 40 is elevated, the piston under these conditions will be at the inner end of its stroke, valve 19 will be open and valve 18 closed (the position of the valves being shown in Figure 3). The handle 33 may then be raised to elevate the piston 15, sufficient suction being produced to fill the lower part of the cylinder with grease from the tank.

The handle 40 is next depressed to reverse the position of the valves, closing valve 19 and opening valve 18, then, upon pushing downwardly on the handle 33 a measured quantity of grease is discharged through the pipes 26 and 27 and out of the nozzle 28. The amount of grease handled by each stroke of the pump may be adjusted and determined by the setting of the screw 34, and it is intended that the nozzle 28 shall be inserted in the receiving port of the casing or box in the gearing or mechanism which is to be lubricated.

Some of the advantages of my invention may be emphasized as follows:

The valve arrangement is such as to permit very large inlet and outlet ports, thus permitting the handling of heavy grease with a relatively small amount of effort and with much greater speed than has hitherto been considered possible. The apparatus is compact and simple—there is nothing to get out of order and is readily carried from place to place.

The variations in size and arrangement of parts may be effected within the spirit and scope of my invention.

40 What I claim is:

1. A dispensing pump for viscous fluids, comprising a cylinder having large inlet and outlet ports at one end, a plunger operating therein, a pair of cylindrically curved valve members slidably mounted on the cylinder, a lever for actuating the plunger, and a valve lever connected to the respective valves and adapted to operate them in alternation.

50 2. A dispensing pump for viscous fluids, comprising a base, a supply tank or box, a cylindrical casing in communication with the tank or box, a cylinder within the casing having inlet and outlet ports with openings in the casing and interposed semi-cylindrical sleeve valves between the casing and the cylinder, and means for alternately opening and closing the valves in conjunctive relation with the inward and outward movement of the plunger.

3. A pump comprising a tubular cylinder having inlet and outlet ports, a plunger in the cylinder, a head formed to provide an annular sleeve projection around the cylinder and concentric therewith, and segmental

cylindrical valves between the sleeve projection of the head and the cylinder for controlling the inlet and outlet ports.

4. A dispensing pump comprising a tubular cylinder having large ports on opposite sides near one end, a plunger in the cylinder, a head having an annular groove to receive the end of the cylinder and formed to provide an annular sleeve projection around the cylinder and concentric therewith, and segmental cylindrical valves between the sleeve projection of the head and the cylinder.

5. A dispensing pump for viscous fluids comprising a base, a supply tank or box, a tubular cylinder having a large inlet port in communication with the tank or box and a large outlet port directly opposite the inlet port, a head formed to provide an annular sleeve projection around the cylinder concentric therewith, and segmental cylindrical valves between the sleeve projection of the head and the cylinder for controlling the inlet and outlet ports.

6. A dispensing pump for viscous fluids comprising a base, a supply tank or box, a tubular cylinder having a large inlet port in communication with the tank or box and a large outlet port directly opposite the inlet port, a head having an annular groove to receive the end of the cylinder and formed to provide an annular sleeve projection around the cylinder and concentric therewith, and segmental cylindrical valves between the sleeve projection of the head and the cylinder.

7. A dispensing pump for viscous fluids comprising a cylinder having an inlet port and an outlet port near one end thereof, a reciprocable piston within the cylinder adapted to draw fluid into the cylinder through the inlet port during one of its strokes and to force said fluid out of the cylinder through the outlet port during its opposite stroke, a pair of cylindrical sleeve valves disposed in longitudinal sliding engagement with said cylinder to open and close the respective inlet and outlet ports and a manually operable linkage mechanism connected to the respective sleeve valves and adapted to concurrently slide the valves in opposite direction to open and close the respective valves in alternation.

8. A dispensing pump for viscous fluids comprising a cylinder having inlet and outlet ports disposed in one end thereof, a reciprocable piston within said cylinder, an operating lever for actuating said piston, a pair of valves for controlling the opening and closing of said inlet and outlet ports, an operating lever connecting the respective valves for concurrently actuating them in alternation preparatory to each successive stroke of the piston and adjustable means carried by said piston operating lever for

determining the length of stroke of said piston whereby a predetermined quantity of fluid is dispensed.

9. A dispensing pump for viscous fluids, comprising a cylinder having an inlet port and an outlet port near one end thereof, a reciprocal piston within the cylinder adapted to draw fluid into the cylinder through the inlet port during one of its strokes and to force said fluid out of the cylinder through the outlet port during its op-

posite stroke, vertically sliding cylindrical means disposed outside of said cylinder and in concentric relation thereto, a lever connected to and for actuating said sliding cylindrical means preparatory to each stroke of the piston to effect a concurrent opening and closing of the inlet and outlet ports in alternation.

In witness whereof I have hereunto signed my name this 26th day of July 1920.

DANIEL F. BEAMAN.
